(57) **CLAIM**

The ornamental design for a clamping device, as shown and described.

DESCRIPTION

FIG. 1 is a front elevational view of a clamping device of a first embodiment of the claimed design.

FIG. 2 is a left side view of the clamping device of FIG. 1.
FIG. 3 is a rear elevational view of the clamping device of FIG. 1.

FIG. 4 is a right side view of the clamping device of FIG. 1.
FIG. 5 is a top view of the clamping device of FIG. 1.
FIG. 6 is a bottom view of the clamping device of FIG. 1.
FIG. 7 is a perspective view of the clamping device of FIG. 1.

FIG. 8 is a front elevational view of a second embodiment of a clamping device of the claimed design.

FIG. 9 is a left side view of the clamping device of FIG. 8.
FIG. 10 is a rear elevational view of the clamping device of FIG. 8.

FIG. 11 is a right side view of the clamping device of FIG. 8.

FIG. 12 is a top view of the clamping device of FIG. 8.
FIG. 13 is a bottom view of the clamping device of FIG. 8; and,

FIG. 14 is a perspective view of the clamping device of FIG. 8.
